UNITED STATES PATENT OFFICE

149,987

DESIGN FOR A SWEATER

Frank M. Titelman, Altoona, Pa.

Application July 10, 1947, Serial No. 140,188

Term of patent 3½ years

(Cl. D3—4)

To all whom it may concern:

Be it known that I, Frank M. Titelman, a citizen of the United States of America, residing at Altoona, in the county of Blair and State of Pennsylvania, have invented a new, original, and ornamental Design for a Sweater, of which the following is a specification, reference being had to the accompanying drawing, forming a part thereof.

In the drawing, the drawing shows a front elevational view of a sweater embodying my design, the back body portion of the sweater being plain except that the serrated ornamentation seen on the lower front continues all the way around the sweater.

The ornamentation shown on the sleeves continues all the way around.

I claim:

The ornamental design for a sweater, as shown and described.

FRANK M. TITELMAN.
